US0D1026571S

(12) **United States Design Patent** (10) **Patent No.:** **US D1,026,571 S**
(45) **Date of Patent:** **** May 14, 2024**

(54) **SPORK**

(71) Applicant: **Sabert Corporation**, Sayreville, NJ (US)

(72) Inventor: **Kam Yiu Wong**, Zhongshan (CN)

(73) Assignee: **SABERT CORPORATION**, Sayreville, NJ (US)

(**) Term: **15 Years**

(21) Appl. No.: **29/823,935**

(22) Filed: **Jan. 20, 2022**

(51) LOC (14) Cl. **07-03**

(52) U.S. Cl.

USPC **D7/643**
